UNITED STATES PATENT OFFICE.

HENRY C. CREEDON, OF TOLEDO, OHIO, ASSIGNOR TO MEBANE BEDDING CO., OF MEBANE, NORTH CAROLINA.

BED-SPRING LOCK.

No. 839,271.

Specification of Letters Patent.

Patented Dec. 25, 1906.

Application filed August 25, 1906. Serial No. 332,035.

To all whom it may concern:

Be it known that I, HENRY C. CREEDON, a citizen of the United States, residing at Toledo, in the county of Lucas and State of Ohio, have invented certain new and useful Improvements in Bed-Spring Locks, of which the following is a specification.

The present invention relates to improvements in bed-springs, and more particularly to a novel locking device whereby the various individual spring members within the frame are held in a fixed position with relation to each other and are prevented from having any lateral displacement.

15 A further feature of the invention resides in the fact that the various elements constituting the lock coöperate with each other to form a series of braces extending throughout the frame.

20 The object of the invention is to provide a lock of this nature which is extremely simple and inexpensive and which can be readily applied without the use of a power stretching-table or other costly apparatus.

25 For a full understanding of the invention and the merits thereof and also to acquire a knowledge of the details of construction of the means for effecting the result reference is to be had to the following description and accompanying drawings, in which—

30 Figure 1 is a top plan view of a portion of a bed-spring constructed in accordance with the invention. Fig. 2 is a sectional view through the same, and Fig. 3 is a perspective view of the lock between the individual springs.

35 Corresponding and like parts are referred to in the following description and indicated in all the views of the drawings by the same reference characters.

The invention is shown as applied to a bed-spring, in which the numeral 1 designates the outer frame, and 2 the individual spring members, which are arranged within the outer frame in a series of parallel rows and which are held relatively in fixed position by means of the locking device. Extending along one side of each of the rows of spring members 2 is a cross wire or strand 3, which is crimped 45 at a point adjacent each of the spring members to form the laterally-extending loops 4, the extremities of which bear against the corresponding spring members 2 in the adjacent

row. These loops 4 preferably comprise the two arms 5, which in the present instance 55 converge, and at their junction with the cross-wire 3 are provided with the offset portions 6, which throw the loops 4 into a plane spaced from the plane of the cross-wires 3. One side of each of the individual spring 60 members 2 is brought into engagement with these offset portions 6 and the spring member thereby effectively held against any lateral displacement in one direction.

Extending across the frame 1 at approximately right angles to the cross-wires 3 and connected to opposite sides of the frame are tie-wires 7, which coöperate with the laterally-extending loops 4 upon the cross-wires 3 to hold the spring members 2 securely in position. These tie-wires or strands 7 extend across the spring members 2 and are provided at suitable intervals with offset portions 8, which pass through the loops 4 and serve the double function of locking the 75 springs 2 in position and of preventing any longitudinal slipping of the tie-wires 7. In the exact arrangement of the various parts it will be observed that the loop 4 has its two members converging throughout their length 80 and that said loop by reason of the offset portion 6 lies straight across the upper side of two adjacent spring members. The tie-wire 7 as it extends from one spring member to the other passes across one spring member 85 contiguous to and between the offset portion 6 and on the opposite side of the spring member from the loop 4, and thence said tie-wire extends to the next spring member and across the same on the side opposite the loop, 90 and thence is offset vertically in substantially ogee formation to project upwardly through the small end of the loop and cross the upper side of the loop, being crimped partially around both the spring member and the 95 cross-connecting portion of the loop, which is joined to the two arms 5, as best seen in Fig. 2. By this arrangement not only do the offsets 8 increase the effectiveness of the tie-wires 7 as braces for the frame, since a tension member is much stronger, (when braced at a plurality of intermediate points than when simply connected at its extremities,) but at the same time it is believed this arrangement promotes economy in the manufacture of the bed-spring bottoms, because it

is much easier to bend a single strand, such as the tie-wires 7, than to bend the two arms 5 at the small end of the loop 4 to secure any crimping and loop effect at this point.

5 With this construction it will be apparent that the various spring members 2 within the frame are each engaged upon opposite sides by the offset portion 6 in the cross-wires 3 and the offset portions 8 in the tie-wires 7, 10 respectively, and are thereby effectively held against any swaying movement or lateral displacement.

An important feature in this invention also resides in the fact that any weight brought 15 to bear against the springs simply tends to tighten the lock and hold the spring members more securely against displacement. Owing to the fact that the locking-wires 7 are formed at intervals with the offset portions 8, the same are held against any longitudinal slipping through the cross-wires 3 and are consequently braced at a series of intermediate points. As a result of this feature a series of brace members are formed 20 25 which not only reinforce the outer frame 1, but also connect the various parallel rows of spring members 2. The formation of the locking device with the offset portions 8 also has the further advantage of enabling the tie 30 to be applied to the frame without the neces-

sity of employing a power stretching-table or other expensive machinery.

Having thus described the invention, what is claimed as new is—

In a bed-spring bottom, the combination 35 of a frame, a plurality of spring members in the frame, cross-wires extending across the frame and provided at intermediate points with loops, the arms of which converge throughout their length, said loops being offset from the plane of the cross-wire and extending straight across one side of two adjacent spring members, and tie-wires extending across the frame at angles to the cross-wires, said tie-wires extending across two 40 adjacent spring members upon opposite sides from the sides where the loops are located, said tie-wires being crimped around the spring members at the small end of the loops and extending upwardly through the small 45 end of the loop and thence across and crimped partially around the cross portion connecting the two converging arms of the loop, as and for the purpose set forth.

In testimony whereof I affix my signature 55 in presence of two witnesses.

HENRY C. CREEDON. [L. s.]
